UNITED STATES PATENT OFFICE.

JOHN J. HOPPES, OF SPRINGFIELD, OHIO.

STEAM-SEPARATOR.

SPECIFICATION forming part of Letters Patent No. 668,818, dated February 26, 1901.

Application filed January 12, 1901. Serial No. 43,084. (No model.)

To all whom it may concern:

Be it known that I, JOHN J. HOPPES, a citizen of the United States, residing at Springfield, in the county of Clark and State of Ohio, have invented certain new and useful Improvements in Steam-Separators, of which the following is a specification.

My invention relates to improvements in steam appliances to separate the water from steam.

The object of my invention is to provide an improved form of separator that is simple in design and will more perfectly separate the water and oil from the steam. In devices of this kind baffle-plates and similar structures have been used, creating tortuous passage, which not only cause friction and "wire-draw" the steam, but also atomize the water of entrainment, and thus increase the saturation.

My object is to secure the highest possible efficiency with the least possible obstruction to the flow of the steam. I attain this object by the construction shown in the accompanying drawings, in which—

Figure 1 is a vertical sectional view of a separator embodying my invention and having the inlet and outlet at right angles to each other. Fig. 2 is a horizontal section taken at X X in Fig. 1 looking in direction of the arrows; and Fig. 3 is a side elevation, partly broken away and with the inlet and outlet both horizontal.

Like parts are represented by similar letters of reference in the several views.

The main body or outer casing *a* of the separator is divided in its upper portion by the diaphragm or horizontal partition *b* and the vertical partition *c* into two chambers, which I will call the "inlet-chamber" *d* and the "outlet-chamber" *e*, said chambers being of a much greater area than the inlet *d* and outlet *e*, which connect with the tops thereof and which may be provided in the usual way with flanges *d*² and *e*² to attach the inlet and outlet pipes. The diaphragm or partition *b* is preferably formed integrally with the partition *c* and the side walls *a*' of the casing *a* and is provided with two openings *b*² and *b*³, one for each of said chambers *d* and *e*. These openings are of smaller area than the chambers, but still of greater area than the inlet

and outlet openings. Said openings *b*² and *b*³ each is surrounded by projecting flanges *b*⁴ and *b*⁵, extending upwardly into and forming with the side walls *a*' and partition *b* gutters *d*³ and *e*³ in the bottom of said chambers *d* and *e* and adjacent to said side walls and partition.

The pipes *f*, attached to the diaphragm *b*, extend at their upper ends into the gutters *d*³ and *e*³, above the bottom thereof, so as to retain water in said gutters, and said pipes extend at their lower ends to the bottom of the chamber *g* to carry off the water from said gutters when it reaches the top ends of said pipes. The water-gage *g*' may be of any well-known form to show the depth of the water in the lower chamber *g*. This water is trapped off through the pipe *g*² in the usual manner. A hand-hole with the plug *g*³ is provided in the bottom of the chamber *g* to give access to same.

The giving up of the moisture of the steam and the tendency of the entrained water to follow the walls of the inclosing parts are largely assisted by a sudden expansion of the steam. To take advantage of this and at the same time provide a greater surface to gather water, the inlet is quickly enlarged into the much greater area of the inlet-chamber, and the opening in the bottom of said chamber being larger than the inlet, but less than said chamber, the steam again expands into the much larger area of the lower chamber.

Provision is made to keep the gutters partially filled with water, for the reason that it has been found that water so held assists in gathering the entrained water and oil, and water is retained in the bottom of the casing for a like purpose.

The inner walls of my separator present smooth surfaces, there being no projections except the gutters, which gather the water and drain it off, my object being to avoid obstructions that will gather water and drop it back into the steam, thereby increasing its saturation.

The steam entering the inlet-chamber rapidly expands and deposits the separated as well as the entrained water into the gutter of said chamber and then through the opening in the bottom of said chamber again expands into the greater lower chamber, the

walls of said lower chamber catching and depositing the water in the bottom thereof, and the bottom of the outlet-chamber being provided with a gutter of like construction with 5 that of the inlet-chamber water that may be retained in the steam and deposited on the walls of said chamber will be gathered by the retained water in said gutter and carried off.

It will be seen that the construction of the 10 inlet and outlet chambers, with their gutters, is such that either chamber can be used as the inlet or outlet. This is sometimes found very desirable, owing to the peculiar situation in which the separator is to be placed.

15 Having thus described my invention, I claim—

In a steam-separator the combination with the outer casing, of a horizontal and a vertical partition dividing said casing into two 20 upper and one larger lower chamber, an opening in the upper portion of each of said upper chambers, one forming the inlet and the other the outlet of said casing, said openings being

of smaller area than the area of said upper chambers, central openings between each of 25 said upper chambers and said lower chamber, having upturned flanges forming with the side walls of said upper chambers, gutters extending entirely around said openings, said central openings each being greater than said inlet-opening but less in size than their respective upper chambers and said gutters formed as described, being the only obstruction in 30 said chambers to the free flow of the steam, drain-pipes extending from a point above the bottom of said gutters so that said gutters will be partially filled with water and water retained in the bottom of said lower chamber to assist in separating the water and oil from the steam, substantially as specified.

In testimony whereof I have hereunto set my hand this 4th day of January, A. D. 1901.

JOHN J. HOPPES.
